T. O. LINDEMAN

OILING AND CLEANING DEVICE FOR GUNS

Filed Feb. 13, 1925

Patented Sept. 8, 1925.

1,552,994

UNITED STATES PATENT OFFICE.

TEDDY O. LINDEMAN, OF WINONA, MICHIGAN.

OILING AND CLEANING DEVICE FOR GUNS.

Application filed February 13, 1925. Serial No. 8,977.

To all whom it may concern:

Be it known that I, TEDDY O. LINDEMAN, a citizen of the United States, residing at Winona, in the county of Houghton and 5 State of Michigan, have invented certain new and useful Improvements in an Oiling and Cleaning Device for Guns, of which the following is a specification.

This invention relates to an oiling and 10 cleaning device for guns, and aims to provide a novel and improved device of this character for conveniently and efficiently cleaning the interior or bore of guns, said device having an oil reservoir carried there- 15 by and means arranged thereon for regulating the flow of oil from said reservoir.

Another object of the invention is to construct the device in a series of detachable 20 sections which will permit the same to be arranged in a compact form when not in use, each of said sections having a valve at each end thereof to prevent leakage of oil contained in the sections and to exclude 25 dust or the like from the interior of the sec- tions.

It is also an object of the invention to provide an oiling and cleaning device of the kind indicated, which is simple and substantial in construction, which can be manufactured 30 economically, and which will be thoroughly efficient and practical in use.

With the foregoing and other objects in view, which will be apparent as the description proceeds, the invention resides in the 35 construction and arrangement of parts, as hereinafter described and claimed, it being understood that changes can be made within the scope of what is claimed, without departing from the spirit of the invention.

40 The invention is illustrated in the accompanying drawings, wherein:

Figure 1 is a side elevation of my improved device,

Figure 2 is a longitudinal section through 45 the upper portion having the reservoir thereon,

Figure 3 is a longitudinal section through the lower portion of the device, and

50 Figure 4 is an enlarged fragmentary section of a portion of the device illustrated in Figure 2.

In carrying out the invention, the numeral 10 designates the handle of the device, which has secured thereto in a detachable manner an elongated rod 11. The handle 55 10 comprises a cylindrical member 12 having the lower end thereof reduced in size, as at 13, to provide a cylindrical, tapered portion, the interior of which engages a like tapered portion 14 carried by the lower end 60 of a sleeve 15 arranged in the cylindrical member 12. The sleeve 15 is enlarged at its lower end adjacent the tapered portion 14 to provide a cylinder 16 in which is slidably mounted a piston 17 carried on the 65 lower end of a slideable rod 18 positioned in the sleeve 15. The upper end of the cylindrical member 12 is screw threaded for engaging a screw threaded portion 19 arranged on a cap member 20, while another 70 portion thereof abuts against the upper end of the sleeve 15, as at 21, said cap 20 having an opening therein through which the slideable rod 18 extends, said rod 18 having the 75 extremity thereof roughened so as to be engaged by a finger of the operator.

Arranged in the enlarged end of the sleeve 15 is a screw threaded bore 22, which receives a threaded projection 23 carried by a coupling member 24. The lower end of the 80 reduced portion 13 of the cylindrical member 12 is slightly longer than the enlarged portion of the sleeve 15 and is adapted to engage in an annular groove 25 provided in the coupling member 24 so as to cause a 85 tight binding action at the engaging tapered portions of the cylindrical member 12 and sleeve 15 when the coupling member is threaded into the enlarged end of the sleeve 15. Positioned in the side wall of the cylinder 16 between the piston 17 and threaded projection 23 is an inlet member 26 having a check valve 27 arranged therein, said check valve normally being closed and adapted to be opened upon the creating of 90 a suction in the cylinder and comprising a ball member 28 engaged by one end of a small coil spring 29, while the opposite end of the coil spring engages a cross pin 30. Arranged between the lower end of the piston 17 and the upper end of the threaded portion 23 is a coil spring 31 for returning 95 100

the piston 17 to its initial position after the same has been operated. Extending through the coupling member is a longitudinal bore 32, the upper end of which is provided with 5 an opening and valve seat 33, said valve seat being adapted to be engaged in a ball or spherical member 34 held in position by a coil spring 35, the opposite end of which is engaged by a threaded collar 36 received 10 in the bore 32 and having an opening 37 therein. The lower end of the bore 32 is threaded as at 38 for receiving a reduced threaded portion 39 arranged on the upper end of the rod 11.

15 The rod 11 is composed of a series of sections 40 arranged to be detachably connected together at the ends thereof, a threaded portion 39 being provided at the upper end of each section, while a threaded socket 20 member 41 is arranged at the lower end of each section. Extending longitudinally through the sections 40 is a bore 42 through which the oil is adapted to flow. At each end of the bore 42 in each section 40 is provided 25 check valves 43 and 44, said check valves comprising spherical members adapted to normally close the bore 42, a coil spring being utilized to serve this purpose. It will be noted that the valves are arranged 30 so that the same will open when oil is forced thereagainst under pressure, and that as soon as such pressure is released the coil springs will close the valves.

35 Threaded into the socket 41 on the lowermost section 40 is a threaded extension 45 carried by an end section 46 having a slot therethrough for receiving a cloth or the like which is used for cleaning the barrel of a gun. The member 46 has a bore 48 extending 40 downwardly from the upper end thereof a slight distance, the lower end of which is branched as at 49 to each side of the member 46.

45 The space between the cylindrical handle member 12 and the sleeve 15 is adapted to form a reservoir 50 for containing the oil, the filling of the reservoir being provided by the removal of the detachable cap 20.

50 In operation, the sectional rod 11 is inserted into the barrel or bore of the gun, and the upper end or roughened surface of the rod 11 forced downwardly, which will cause the oil contained in the cylinder 16 to open the ball valve 34, as said oil will be 55 under pressure. The opening of the valve 34 will permit the oil to be forced to each of the valves in each section 40 of the rod 11 by forcing the piston downwardly several times, the spring 31 returning said piston 60 to its initial position. Such returning of the piston will create a suction in the cylinder 16 and cause the ball valve 38 to unseat and permit a fresh supply of oil to enter the cylinder 16 from the reservoir 50. It will 65 be noted that by intermittently pressing the

rod 18 downwardly that the oil will be forced past each of the check valves in the rod 11 until the same is forced through the branch opening 49 in the slot carrying section 46 of the device. 70

When the device is not in use and it is desired to have the same in a compact form, the threaded ends of each section are disconnected and may be laid side by side in order to be conveniently carried by the user 75 from place to place. When in such a disconnected or compact form the check valves at each end of each section and the valves in the reservoir will prevent the leakage of oil contained in each section and will also prevent dirt or the like from gaining access to the interior of said sections. 80

Having thus described my invention, what I claim as new is:

1. An oiling and cleaning device for guns 85 comprising a rod having a longitudinal bore therein opening to the atmosphere at one end of the rod, means for supplying oil to the bore in said rod, said rod being constructed of a series of sections detachably 90 connected together, and means at the connecting portions of the sections for closing the bore therein.

2. An oiling and cleaning device for guns comprising a rod having a longitudinal bore 95 therein, means for supplying oil to the bore of said rod, said rod being constructed of a series of sections detachably connected together, and check valves arranged at the connecting portions of the sections for closing 100 the bore therein.

3. An oiling and cleaning device for guns comprising a rod having a longitudinal bore therein, an oil reservoir carried by one end of said rod, a cylinder arranged in said reservoir, a piston slidably mounted in said cylinder, and check valves arranged in said cylinder for supplying oil from the reservoir to the bore of the rod upon movement of 105 said piston.

4. An oiling and cleaning device for guns comprising a rod having a longitudinal bore therein, said rod constructed of a series of detachably connected sections, an end section attached to said rod and having openings therein communicating with the bore in said rod and with the atmosphere, check valves arranged at the opposite ends of said sections for normally closing the bore therein, an oil reservoir carried by the end of said rod opposite to that carrying said end section, a cylinder arranged in said reservoir, a piston slidably mounted in said cylinder, a bar attached to said piston for manually operating the same, a pair of check valves arranged for supplying oil from the reservoir to the longitudinal bore in said rod upon operation of the piston in the cylinder, and a spring arranged for returning the piston after the same has been operated. 110 115 120 125 130 135

1,552,994

5. An oiling and cleaning device for guns comprising a rod having a longitudinal bore therein, an end section carried by said rod and having openings therein communicating with said bore and atmosphere, means arranged at the opposite end of said rod for feeding oil to the bore under pressure, said rod being constructed of a series of sections detachably connected together, and check valves arranged at the opposite ends of said sections adapted to open to permit oil to flow to and from the bore within the sections when oil is fed to said valves under pressure.

In testimony whereof, I have affixed my ¹⁶ signature.

TEDDY O. LINDEMAN.
